Primary Examiner — Phillip S Hyder*(74) Attorney, Agent, or Firm* — Aleksander Medved(57) **CLAIM**

The ornamental design for a masking article, as shown and described.

DESCRIPTION

FIG. 1 is a perspective view of a masking article embodying the new design;

FIG. 2 is a front elevation view of thereof;

FIG. 3 is a right side elevation view thereof, the left side elevation view being a mirror image; and,

FIG. 4 is a top plan view thereof, the bottom plan view being a mirror image.

The broken lines depict portions of the masking article in which the design is embodied that are not considered part of the claimed design.
